STOP MECHANISM

John H. Sayres, Chappaqua, N. Y.

Application June 16, 1934, Serial No. 730,988

19 Claims. (Cl. 192—116.5)

This invention relates to stop mechanisms of the type disclosed in my prior Patent No. 1,628,474 granted May 10th, 1927, and has for its principal object to simplify and improve and reduce the cost of manufacture of stop mechanisms of this character. As distinguished from the toggle mechanism of my prior patent, the present invention employs a lever having unequal lever arms.

Other objects will become apparent as the following description proceeds, as read in conjunction with the accompanying drawings, in which—

Figure 1 is a detail perspective view of the stop mechanism according to the preferred embodiment of the present invention;

Figure 2 is a detail of the retaining member in actuator retaining position;

Figure 3 is a similar view of the same in releasing position;

Figure 4 is a side elevation of a modification of the stop mechanism with the cover broken away;

Figure 5 is a vertical section taken along the line 5—5 of Figure 4;

Figure 6 is an end elevation of the retaining member for the modification; and

Figure 7 is a side elevation of the same.

The stop mechanism comprises an actuator 10, which may be connected in any known manner to the machine or instrumentality to be stopped thereby, for any of the purposes set forth in my prior patent, and is urged in one direction by a spring 11. This actuator has an abutment 12, which in the preferred embodiment shown, comprises the end of a notch cut into the actuator 10.

A retaining member 13 is provided for holding the actuator 10 against the action of the spring 11. The retaining member has a pivot 14, and is provided with an abutment 15 cooperating with the actuator abutment 12 and an arm 16 extending laterally from the pivot 14, and engaged at its free end by a latch 17.

In the automatic electric stop mechanism shown, the latch 17 constitutes the armature of an electromagnet 18. The magnet circuit includes one or more pairs of contacts arranged as shown and described in my prior patent to be closed by the condition which renders actuation of the stop mechanism desirable. A circuit breaker 19 is provided for the magnet circuit, and is arranged to be operated by a moving part of the stop mechanism.

In operation, closing the contacts energizes

the electromagnet 18, which pulls down the latch 17. This frees the outer end of the arm 16, and the force of the spring 11 transmitted by the actuator 10 and its abutment 12 to abutment 15 of the retaining member 13 and turns it with the arm 16 as a unit about the pivot 14, through an arc of about 90°.

As the retaining member 13 turns the abutment 15 turns with it, and a flat portion of the retaining member comes into position parallel to the actuator 10. As this flat portion is but a relatively small radial distance from the pivot 14, it clears the actuator 10 when it is parallel thereto, thus releasing the actuator for movement under the force of the spring 11.

When the actuator is returned to reset the stop mechanism, the spring 11 being thereby extended, the spring 22 causes return rotation of the retaining member, as soon as the actuator abutment 12 passes the retainer abutment 15, thus swinging the arm 16 to set position. This return swing of the arm 16 causes the end thereof to engage the cam portion 21 of the latch 17, and depress the same until it rides off the end. The spring 23 then returns the latch 25 to set position, in which it remains until the control contacts are closed again.

In the form shown in Figure 1, the automatic electric stop mechanism is housed in a casing 25. The actuator bar 10 slides through guides 26 formed in bosses in the casing wall. The casing 25 is preferably rectangular, having side walls 28, 29, 30 and 31. The pivot 14 is near the corner thereof formed by the junction of walls 28 and 29, and has bearings 27 in bosses in the front and back of the casing. The actuator 10 is near the bottom wall 28 of the casing, just above the pivot 14.

The retainer member 13 is shown with a rectangular portion, but it may be of any other cross-section and provided with an abutment face, and the arm 16 extends at right angles to the rectangular portion. The armature 17 is near the top wall 30 and is pivoted at 24 in the corner formed by walls 30 and 31. The magnet 18 is located between the actuator 10 and the latch 17, being mounted on an angle clip secured to the back of the casing. The circuit breaker is also mounted on this clip, and insulated therefrom and comprises a pair of spring contact blades 20 in the magnet circuit and adapted to receive a conductor disk 19 carried by the arm 16 and insulated therefrom.

Thus the arm 16 swings from a position adjacent the wall 29 to a position adjacent the

wall 28, passing in front of the magnet 18, and promptly breaking the circuit therethrough. With this arrangement, the parts are very compact and at the same time, the maximum length 5 of the arm 16 is available for leverage, while the length of the abutment 15 is reduced to a minimum. Also, the engagement of the latch 17 with the end of the arm 16 is edge to edge, so that a minimum latch movement is required for 10 release.

A modified embodiment of the invention is shown in Figures 4, 5, 6 and 7. Here the actuator is a cable wound on a drum, and a trip device is added to permit more than one revolution 15 of the drum.

One end of the cable 49 is secured to the drum 50 which is urged to rotate in one direction by a spiral spring 51. The abutment 52 of the actuator is formed by the side of a notch 20 cut into the flange of the drum 50.

The retaining member 53, which holds the actuator against the action of the spring 51, has a pivot 54, and an abutment 55 cooperating with the actuator abutment 52. An arm 56 extends laterally from the pivot 54 and is engaged at 25 its free end by a latch 57 preferably forming the armature of the electromagnet 58, the circuit of which, as described for the preferred embodiment, includes the control contacts and a circuit breaker 59 arranged to be operated by 30 a moving part of the stop mechanism.

This circuit breaker comprises an upper conductor blade 60 and a lower spring contact blade 61, both mounted on and insulated from the base 35 of the housing. The spring contact blade 61 is normally in contact with the turned down outer end of the upper conductor blade 60.

A trigger 40 is pivoted at 41 near the actuator 40 and the retaining member 53. This trigger is in the form of a bell crank, the arm 40a of which has a lug 42 adapted to enter a slot 43 in the retaining member 53. The other arm 44 is faced with insulating material 44a and operates the circuit breaker 59 by engaging the projecting end of the lower spring contact blade 45 61. A spring detent 45 selectively engages notches 46 and 47 to hold the trigger in its two respective positions. A trip button 48 is secured to the cable 49, in position to engage the trigger 40.

In operation, closing the contacts energizes the electromagnet 58, which pulls down the latch 57. This frees the outer end of the arm 56, and the force of the spring 51 is transmitted by the actuator 50 and its abutment 52 to abutment 55 of the retaining member 53 and turns it with the arm 56 as a unit about the pivot 54, through an arc of about 90°.

As the retaining member 53 turns the abutment 55 turns with it, and the flat portion of the retaining member comes into position approximately parallel to a tangent to the circumference of the flange of the drum 50. As the flat portion is but a relatively small radial distance from the pivot 54, it clears the drum 50 and its flange, thus releasing the actuator for movement under the force of the spring 51.

However, the spring 51 winds up the cable 49 on the drum 50, and the button 48 on the cable 70 engages the trigger 40 and moves it from the full line position shown in Figure 4, with the spring detent 45 engaging the notch 46, to the dotted line position in which it engages the notch 47. This causes the lug 42 to enter the 75 slot 43, and at the same time causes the arm

44 to open the circuit breaker 59, by depressing the blade 61 out of contact with the blade 60.

The lug 42 holds the retaining member 53 against the action of spring 62, so that the spring 51 can cause more than one revolution 5 of the drum 50, and wind up several convolutions of the cable 49, because the abutment 55 is held clear of the abutment 52 in the notch in the flange of the drum.

To return the actuator to reset position, the 10 cable 49 is pulled to unwind the same from the drum 50, thereby winding up the spring 51. At the final revolution, the button 48 re-engages the trigger 40 and moves it back to the full line position, with the notch 46 engaging the detent 45. This moves up the arm 44 and releases the circuit breaker blade 61, and also withdraws the lug 42 from the slot 43, which releases the retaining member 53. Hence, when the notch in the flange of the drum 50 comes 15 around to the retaining member 53, the spring 62 rotates it back to its original position, because the retaining abutment 55 is free to enter the notch and engage the actuator abutment 52, thus swinging the arm 56 to set position 20. This return swing of the arm 56 causes the end thereof to engage the cam portion 64 of the latch 57 and depress the same until it rides off the end. The spring 63 then returns the latch 25 57 to set position in which it remains until the 30 contacts are closed again.

While two embodiments of the invention have been disclosed, the invention is not limited to the details thereof, but instead embraces such modifications of the broad idea as fall 35 within the scope of the appended claims.

What I claim is:

1. In a stop mechanism comprising an actuator and means urging said actuator in one direction, the combination of a pivoted retaining member having a stationary axis, cooperating abutments on said retaining member and said actuator, a latch for said retaining member, and means for operating said latch to release said retaining member.

2. In a stop mechanism comprising an actuator and means for urging said actuator in one direction, the combination of a member having one end pivoted about a stationary axis adjacent to said actuator, latching means engaging the other end of said pivoted member and an abutment on said pivoted member engaging said actuator.

3. In a stop mechanism comprising an actuator having an abutment, and means for urging said actuator in one direction, the combination of a pivoted retaining member having an abutment extending into the path of and cooperating with said actuator abutment, an arm movable with said retaining member about its pivot, a latch engaging said arm, and means for moving said latch clear of said arm, said retaining member having a portion of lesser radial extent than its abutment.

4. In a stop mechanism comprising an actuator having an abutment, means for mounting said actuator for movement of said abutment in a predetermined path, and means urging said actuator to cause movement of said abutment along said path in one direction, the combination of a pivoted retaining member extending into said path, an arm on said retaining member, a latch engaging said arm, and means for moving said latch clear of said arm, said re- 75

taining member having a flat portion clear of said path when parallel thereto.

5. In a stop mechanism comprising an actuator and means for urging said actuator in one direction, the combination of a casing having side walls, a member pivoted about a stationary axis in said casing to swing from a position adjacent one side wall to a position adjacent the next side wall, means in said casing engaging said member, and an abutment on said member 10 engaging said actuator.

6. In a stop mechanism comprising an actuator and means for urging said actuator in one direction, the combination of a casing having 15 side walls, a member pivoted in said casing adjacent the junction of two of said side walls and adapted to swing from a position adjacent one to a position adjacent the other, means in said casing adjacent a third of said side walls 20 and engaging said member, and an abutment on said member engaging said actuator.

7. In an automatic electric stop mechanism comprising an actuator and means for urging said actuator in one direction, the combination 25 of a casing adapted to receive said actuator, a retaining member pivoted about a stationary axis in said casing and having an abutment engaging said actuator, an arm on said retaining member, a latch engaging said arm, and an electromagnet in said casing for operating said latch, said arm being positioned axially of said retaining member to clear said magnet when released by said latch.

8. In an automatic electric stop mechanism comprising an actuator and means for urging said actuator in one direction, the combination 30 of an arm pivoted about a stationary axis at one side of said actuator member, an electromagnet having an armature engaging said arm, an abutment on said arm engaging said actuator member, a circuit breaker, means for operating said circuit breaker when said arm is released by said armature, and means for automatically resetting the stop mechanism when 35 said actuator is returned.

9. In an automatic electric stop mechanism comprising an actuator having an abutment, means for mounting said actuator for movement of said abutment in a predetermined path, and 40 means urging said actuator to cause movement of said abutment along said path in one direction, the combination of a pivoted retaining member having an abutment extending into said path and cooperating with said actuator abutment to retain said actuator against the action 45 of said urging means, an arm movable with said retaining member about its pivot, a latch engaging said arm, and an electromagnet for moving said latch clear of said arm, said retaining member having a portion of lesser radius than its abutment, whereby when said latch is released by said electromagnet, said urging means causes said actuator abutment to move said retaining member about said pivot, and bring said portion of lesser radius into 50 position opposite said path, thereby permitting said actuator abutment to pass said retaining member.

10. In a stop mechanism, in combination, a 55 pivoted actuator, means urging rotation of said actuator about its pivot in one direction, a pivoted retaining member having a stationary axis, cooperating abutments on said retaining member and said actuator member, an element rigid with said retaining member, a latch engaging

said element and means for moving said latch clear of said element.

11. In a stop mechanism, in combination an actuator comprising a drum having a cable wound thereon, means for urging said drum to rotate in one direction, an arm pivoted about a stationary axis adjacent one end at one side of said drum, latching means engaging the other end of said arm, and an abutment on said arm engaging said drum. 10

12. In a stop mechanism, in combination, a rotary actuator, means for urging rotation of said actuator in one direction, a pivoted retaining member having a stationary axis, cooperating abutments on said retaining member and 15 said actuator for preventing said rotation, an element rigid with said retaining member, a latch engaging said element, means for moving said latch clear of said element, and means for holding said retaining member abutment clear of said actuator abutment for more than one revolution of 20 said actuator.

13. In a stop mechanism, in combination, an actuator, means for urging said actuator in one direction, a pivoted retaining member having a 25 stationary axis, cooperating abutments on said retaining member and said actuator, an element rigid with said retaining member, a latch engaging said element, means for moving said latch clear of said element whereby said urging 30 means causes said abutments to move said retaining member about its pivot, and means for holding said retaining member in its second position.

14. In a stop mechanism comprising an actuator and means for urging said actuator in one direction, the combination of a pivoted arm having a stationary axis, an electromagnet having an armature engaging said arm, an abutment rigid with said arm and engaging said actuator, 40 a circuit breaker, and means for operating said circuit breaker when said arm is released by said armature and for holding said arm in released position.

15. In a stop mechanism comprising an actuator having an abutment, means urging said actuator to cause movement of said abutment in an arcuate path, the combination of a pivoted retaining member having an abutment extending into said path, an arm movable with said 50 retaining member about its pivot, a latch engaging said arm, means for releasing said latch, said retaining member having a portion of lesser radius than its abutment whereby when said latch is released, said urging means causes said 55 actuator abutment to move said retaining member to bring said portion of lesser radius into position opposite said path, and means for holding said retaining member in said position to permit said actuator abutment to repeatedly 60 pass said retaining member.

16. In a stop mechanism comprising an actuator and means urging said actuator in one direction, the combination of a pivoted retaining member having a stationary axis, cooperating 65 abutments on said retaining member and said actuator, a latch for said retaining member, means for releasing said latch and means for resetting said retaining member and latch upon restoring said actuator to position for engagement by the retaining member. 70

17. In a stop mechanism comprising an actuator and means urging said actuator in one direction, the combination of a pivoted retaining member having a stationary axis, cooperating 75

- abutments on said retaining member and said actuator, a latch for said retaining member, an electromagnet for releasing said latch and controlling means for the magnet circuit operated upon movement of said retaining member.
18. In a stop mechanism comprising an actuator and means for urging said actuator in one direction, the combination of stop means pivoted about a stationary axis for preventing movement of said actuator by said urging means and means for holding said stop means disengaged from said actuator.
19. In a stop mechanism, comprising an actuator and means for urging said actuator in one direction, the combination of stop means pivoted about a stationary axis for preventing movement of said actuator by said urging means, means for disengaging and holding said stop means disengaged from said actuator and means for resetting said stop means upon restoring said actuator. 5

JOHN H. SAYRES. 10
